UNITED STATES PATENT OFFICE.

MANUEL BRETOS Y CLAVERIA, OF SANTIAGO, CUBA.

LOCK FOR CASES.

Application filed June 11, 1921. Serial No. 476,750.

To all whom it may concern:

Be it known that I, MANUEL BRETOS Y CLAVERIA, a subject of the King of Spain, and resident at Santiago, Cuba (whose postal address is No. 22 Gallo Street, Santiago, Cuba), have invented certain new and useful Improvements in Locks for Cases, of which the following is a specification.

This invention relates to locks for cases, particularly to cases designed for keeping jewelry or important drawings, papers and documents which require to be safely kept, and its main object is to provide a safety lock for cases and the like which render the same practically as safe as the usual cash-boxes or safes.

The invention is described with reference to the figures of the annexed drawings, in which:

20 Fig. 1 is a side elevation of the case forming the subject matter of this invention.

Fig. 2 is a side elevation showing the case inserted in a proper box or casing therefor.

25 Fig. 3 is an upper plan view thereof.

Fig. 4 is an enlarged detailed side elevation of the case cover and the box containing the safety-lock mechanism.

Fig. 5 is an upper plan view thereof.

30 Fig. 6 is a vertical section on line 6—6 of Fig. 5.

Fig. 7 is a horizontal section on line 7—7 of Fig. 6.

35 Fig. 8 is a detailed perspective view of the device used for preventing the documents and drawings kept in the case from becoming unrolled.

Fig. 9 is an enlarged vertical section of the lid or cover and box containing the 40 safety-lock mechanism.

Fig. 10 is a plan view of the lower face of the lid or cover and box containing the safety-lock mechanism.

Fig. 11 is a horizontal section on line 45 11—11 of Fig. 9.

Fig. 12 is the same section showing another operative position of the safety-lock mechanism.

Fig. 13 is a horizontal section on line 50 13—13 of Fig. 9.

Fig. 14 is a horizontal section on line 14—14 of Fig. 9.

Fig. 15 is a detail horizontal section, on a plane intersecting one of the bolts 38.

55 Fig. 16 is a similar view, showing the bolt in withdrawn position.

Fig. 17 is a detail perspective view of one of the bolts 38 and one of the arms 37.

In the drawings there is represented a case whose main body 1 consists of a hollow cylindrical tube bearing on a base 2. The lid or cover 3 of the case is mounted on a box 4 having open ends and of cylindrical form, divided in two compartments, an upper one 5 and a lower one 6 by a horizontal partition 7. Said cover is secured by means of screws 8, which pass through holes in the partition 7 and the upper ends of the screws being threaded in shoulders 9 which project from the lower face of the lid 3. This lid is provided at its upper face with a disc having beveled edges 10 and arranged to rotate in a circular flange 11. Said disc is numbered in the usual manner. Disc 10 has a button 12 and a rectangular section 75 stem 13 which is designed to operate in the recess piece of the safe-lock as will be hereinafter explained.

Within the upper compartment 5 of the box 4 is a flat casing of rectangular form 14, 80 which is secured with respect to partition 7 by means of screws 15 which are threaded in registering holes in said partition 7. Casing 14 is provided with a removable lid and within the same is inclosed a safety mechanism constituted by discs 16 arranged one on the other, each having an opening, its arrangement and construction being such as the usual one in this class of safe-locks, as will become evident to those expert in the 90 art. Extending through said discs is a member 18 in which fits the stem 13 of button 12. Said member 18 is mounted in a bearing in a piece 19, provided also with an elongated slot 19' and with a narrower elongated slot 95 19''. A hollow stem 20 fixed to the bottom of the casing and vertically projecting therefrom, passes through the slot 19'' and is threaded to admit a screw for securing the lid of the casing in position. The opposite 100 end of piece 19 terminates in a flange which is bent down and bears against one of the edges of a side of casing 14. At one side of casing 14 is a horizontal slot through which passes a bolt 22 terminating rearwardly in 105 the inner part of the casing in two fork shaped branches 23 and 24. At the inner end of branch 23 there is articulated a curved detent which bears on the outer edges of the discs 16 the same being pressed against said 110 discs by means of a spring 26. From the lower face of branch 24 projects a vertical

peg 27 which passes through a guide slot 28 in the partition 11 and also a guide slot 29 transverse to the slot 28 in a disc 30 covering the bottom of a compartment 31 arranged centrally to the lower compartment 6 of box 4 and surrounded by a circular wall 32 integral with the face of partition 7. Disc 30 is arranged to rotate around a short vertical shaft 33 projecting down from the center of partition 7 and which passes through a stem 30' integral with disc 30, terminating in a head 33'. In the same disc 30 is a circular opening 34 which is arranged to register with another opening 35 in the partition 7 which forms the bottom of the compartment 9 in which the safe-lock mechanism is inclosed. In the wall of the upper compartment 5 there is an opening 34' to admit a tool whereby the mechanism may be actuated.

Around shaft 33 on screws 36 constituting short vertical shafts are articulated four horizontal connecting arms 37 whose outer ends terminate in forked heads between which are pivoted the tapered ends of four horizontal bolts 38 projecting through registering openings 39 and 40 in the circular wall 32 and in the wall of box 4 respectively. Said bolts in the closed position of the lid 3 engage their free tapered ends in an annular slot 41 on the inner side and at the upper part of the wall of the main body 1 of the case. The lower compartment 6 is closed by a threaded lid 42 provided with a glass 43, to prevent dust or dirt being introduced in the mechanism.

Inside the main body 1 of the case and forming a separable body therewith there is a device, which, as illustrated in Figs. 6 and 8 of the drawings comprises a plane base plate in cross shape 44 and centrally thereon is fixed a circular plate 45 whose edges are bent down to form flanges having slots 46 which are spaced apart so that between each two of them may pass a long metal hoop 47 which is upwardly curved and terminate in inwardly projecting claws 47'. At the center of the upper face of the base plate 44, surrounded by the hoops 47, is fixed a vertical rod 48 which passes through the securing plate 45 and terminates in a button 49 this rod being adapted for use in rolling around the same the drawings or documents which it may be desired to keep within the case so that when the device is introduced into the main body of the case, the hoops 47 are pressed inwardly and by their tension prevent the unrolling of the documents disposed around the rod 48.

The case can be inserted in another proper casing of leather 50 as illustrated in Fig. 2, which latter is provided with a handle 51 and a proper fastener 52.

The safe-lock mechanism of the case operates as follows: Assuming the lid 3 and

the box 4 fitted in the upper part of main body 1 as illustrated in Fig. 6, in the closed position the four bolts 38 will be inserted in the annular slot 41 of main body 1 of the case. When it is desired to open the same, the button 12 carrying the disc 10 will be operated in the usual manner known for opening safe locks, turning the discs 18 actuated by the stem or male piece 13 fitted in the female piece 18 until the slots 17 of each one of the discs may register with the respective slots of each one of the other discs whereby the detent 25 will fall into the superposed slot 16 as illustrated in Fig. 11, and upon turning the disc 10 in the direction illustrated in Fig. 12, the discs 16 will move the bolt 22 inwardly and the pin 27 projecting down the branch 24 of the bolt will slide along the slot 28 and the registering and transverse slot 29 of the disc 30, whereby the latter will rotate and the arms 37 which were in alinement with its respective bolts 38 as illustrated in Figs. 10 and 16 will move out of alinement and the bolts 38 will draw into the compartment 6 through the openings 39 and 40 as illustrated in Fig. 17 whereupon the lid 3 and the box 4 can be taken off, thus opening the case.

Effecting an opposite motion with button 12 which turns disc 10 discs 16 will be disconnected from one another, the spring 25 coming out of engagement with the slots 17 and the bolt 22 on moving outwardly will carry the disc 30 by the pin connection 27 and slots 28-29, the four bolts 38 coming again in alinement with arms 37 and being accordingly inserted into the annular slot 41.

Having thus described my invention and the form in which the same is carried out, what I desire to protect with Letters-Patent is all that which may fall within the scope of the appended claim.

What I claim is:—

In cases for keeping jewelry and documents and which are locked by the insertion of a plurality of bolts movably connected to the lid or door of the case into an inner slot or recess of the case body, the combination with a safety mechanism arranged in the upper compartment of a box carried by the lid or door and divided by a horizontal partition in two compartments, of a fork-shaped piece slidably mounted in the upper compartment of said box and carrying a stem vertically projecting downwards through a slot in the horizontal partition and through another slot transverse to the above slot in a disc gyratory mounted below the partition on a vertical shaft fixed at the center of the partition in the lower compartment of the box, a circular wall projecting downwards from the horizontal partition and surrounding said disc in the lower compartment of said box, a plurality

of arms pivoted at one end to said disc in an equi-distant manner around the vertical shaft and articulated at their free ends with corresponding horizontal lock bolts slidably mounted through openings in the circular wall corresponding with openings in the wall of the box, said lock bolts being adapt-

ed to engage the inner slot or recess of the case, and connecting means between the shaft and articulated at their free ends with safety mechanism and said fork-shaped piece to operate the latter in operating the safety mechanism.

In witness whereof I affix my signature.

MANUEL BRETOS y CLAVERIA.
